ELECTRIC ALARM FOR LOCOMOTIVES.

No. 330,074.

Patented Nov. 10, 1885.

UNITED STATES PATENT OFFICE.

WILLIAM VOGEL, OF CHICAGO, ILLINOIS, ASSIGNOR TO ADOLPH ZELLER,
OF SAME PLACE.

ELECTRIC ALARM FOR LOCOMOTIVES.

SPECIFICATION forming part of Letters Patent No. 330,074, dated November 10, 1885.

Application filed March 20, 1884. Renewed September 1, 1885. Serial No. 175,897. (No model.)

To all whom it may concern:

Be it known that I, WILLIAM VOGEL, of Chicago, in the county of Cook and State of Illinois, have invented certain new and useful 5 Improvements in Electric Alarms or Signals for Locomotives, &c.; and I do hereby declare the following to be a full, clear, and exact description of the invention, such as will enable others skilled in the art to which it pertains 10 to make and use it, reference being had to the accompanying drawings, which form part of this specification.

My invention relates to an improvement in electric alarms or signals for locomotives on 15 approaching switches, stations, bridges, &c.; and it consists in the combination of a number of electrical contacts, corresponding to the number of tracks with which the switch connects, and which are electrically connected to 20 a corresponding number of contacts which are placed at the switch, a switch-rod which is connected with the ground-battery, and which is provided with a device for resting upon one of the contacts, a ground-battery 25 which is connected to the rails of the main track, and a suitable operating mechanism placed upon the locomotive for the purpose of sounding an alarm and exposing a sign or signal to the engineers, showing whether it 30 is safe to proceed or not.

The object of this invention is to attract the attention of the engineer in passing a certain point which is distant from the switch, and, by exposing a signal or sign, notify him 35 whether the switch is making connection with the right track or not.

Figure 1 is a plan view of the track and the connections. Fig. 2 is a detail view showing the connections between the contacts on the locomotive and those on the track. Fig. 3 shows 40 the connection between the switch and the contact points. Fig. 4 shows the electrical apparatus on the locomotive. Fig. 5 shows the connection between the electro-magnets and the drops. Fig. 6 shows the signs used 45 on the locomotive to notify the engineer. Figs. 7 and 8 are detail views of the electro-magnets; Figs. 9 and 10, different views of a modification.

50 A represents the main track; B, the switch, and C the switch-arm for moving the switch

so as to connect the main track A with any one of the tracks on beyond the switch. At any suitable distance from this switch, in between the rails of the main track, will be a 55 suitable number of contact-points, G, (shown especially in Fig. 2,) and which will project any suitable distance up above the tops of the main rails of the track. Of these contacts G there is a number corresponding to the number of tracks with which the switch B connects. 60 Each contact G is insulated from the cross-tie upon which it is placed by a suitable bed or cushion of rubber, or any other suitable substance. This rubber serves both to 65 insulate the contacts G and to allow them to be bent slightly forward when struck by the locomotive, as shown in dotted lines, so as to allow the locomotive to pass freely over them. Each one of these contacts G is connected by 70 means of a wire, D, which runs along upon the poles placed by the side of the track to the corresponding insulated contacts, E, placed just beside the switch-rod. Connected to the switch-rod C is a ground-battery, M, and connected to the rails of the main track, near the contact-points G is a second ground-battery, 75 L. Secured to the switch-rod of the lever is a short arm, F, to the outer end of which is connected a wheel or other similar device, H. 80 When the switch-rod is moved so as to make the switch B connect with any one of the tracks which connect with the main track, this wheel H is made to move along over the tops of the contacts E, which are suitably arranged for the purpose, and whenever the switch B is made to connect with one of the tracks this wheel H rests upon the top of the corresponding contact, so as to make electrical connection with the corresponding contact G, 85 by means of the wire D. By this construction it is impossible to move the switch-lever without forming an electrical connection between the corresponding contacts E and G, for the purpose of communicating with the engineer when 90 the locomotive passes over the contacts G.

To the under side of the cow-catcher of the locomotive will be secured the cross-bar K, to the under side of which are secured a number of curved contacts, I, which are arranged in 100 such relation that when the locomotive passes over the contacts G, every one of the contacts

I will make connection with the corresponding contacts, G, and as the contacts I pass over the contacts G the contacts G will be forced forward, as shown in Fig. 2. Each contact I 5 on the locomotive, of which there will be a number corresponding to the number of the contacts G, is connected by means of a wire, J, with the pairs of electro-magnets N. There is a pair of these electro-magnets N for each 10 of the contact-points G, and for each of the electro-magnets there is an armature, O, and a corresponding sign or signal, P, and drop Q.

Upon the locomotive, at any suitable point, is placed a battery, R, which connects with 15 the pairs of electro-magnets N and with the frame S at one pole, and with the boiler or any other suitable part of the locomotive at the other pole, and to the alarm-bell S'. The current which is connected with the locomotive 20 is intended to pass down through the wheels to the main track, and thus form connection with the currents which pass from the ground-batteries L M. From one pole of the battery passes the wire T, which connects with the 25 alarm-bell S' and the wire U from the other pole, for connecting with the electro-magnets and the insulated frame S. From the alarm-bell extends the wire V, for the purpose of connecting with the insulated support W, up- 30 on which the drops Q fall.

When a current is passed through any one pair of the electro-magnets N in passing over the contacts G, the armature O is drawn downward, which releases a drop, Q, from the hook 35 end of the armature, and the drop falls upon the support W, which is suitably insulated from the frame S, and connected by the wire V to the alarm-bell S'. When the drop Q falls, a sign or signal of any suitable kind— 40 such as is shown in Fig. 6—is exposed at the same time that the alarm-bell S' is sounded by the passage of a current through the frame, support W, wires V T, and alarm-bell. A glance at the sign or signal exposed shows the engineer whether it is safe to proceed or not. For instance, the locomotive is moving in 45 the direction of the switch, and the contact-points I on the locomotive strike against the contact-points G. As above described, moving the switch-rod into any desired position makes electrical connection between one of the contacts G and one of the contact-points E by stopping the wheel H upon one of the contacts E. If the connection is not to be made with 50 that portion of the main track which is beyond the switch, and the switch is moved so as to connect with this portion, this wheel H will rest upon the central contact, E. Then the cor-

responding contacts, G I, are in condition to have a current passed through them, through 60 the wire J, through the corresponding pair of electro-magnets, N, and the battery. The armature O, being drawn downward by the closing of the circuit, the drop Q falls and the alarm-bell instantly sounds for the purpose of 65 attracting the engineer's attention to the sign "wrong track," which is exposed by the falling of the drop Q. When the contacts I G make connection, a circuit is passed through one of the wires T, electro-magnets N, wire V, 70 battery R, through the boiler, through the wheels, the rails of the main track, down to the ground L, through the ground to M, through the switch-rod C, wheel H, contacts E, wire D, and contact G. 75

When it is simply desired to show the engineer where he is on the track at night or in foggy weather, the contacts G on the track will be made wider, and then there will be two contacts, I, on the locomotive for each one G, 80 and no wires D or switch. When contact is made between the one, G, on the track and the two contacts I on the locomotive, a current is passed from the battery down through the three contacts back through the wires J, elec- 85 tro-magnet, to the other pole of the battery. These contacts may be arranged along the track at any desired point, and used to indicate bridges, curves, crossings, and stations, and each contact will have its corresponding 90 sign, so as to let the engineer see just where he is or what he is coming to.

Having thus described my invention, I claim—

1. The combination of a battery on the locomotive, electro-magnets and signals connected thereto, wires leading from the magnets, and suitable contact-points on the locomotive with contact-points at a suitable distance from the switch, contact-points at the switch, and 100 wires for connecting the two sets of contact-points together, the switch-lever provided with means of connection with the contact-points at the switch, and the ground-batteries, substantially as shown and described. 105

2. The combination of the ground-contacts, contacts on the locomotive, wires J, electro-magnets, armatures, drops, frame, support for the drops to fall upon, battery, and connecting-wires, substantially as set forth. 110

In testimony whereof I affix my signature in presence of two witnesses.

WILLIAM VOGEL.
